UNITED STATES PATENT OFFICE.

HUGH A. COLE, OF CHICAGO, ILLINOIS, ASSIGNOR TO COLE MANUFACTURING COMPANY, OF CHICAGO, ILLINOIS, A CORPORATION.

STOVE.

1,387,453.

Specification of Letters Patent. Patented Aug. 16, 1921.

Application filed January 5, 1920. Serial No. 349,515.

To all whom it may concern:

Be it known that I, HUGH A. COLE, a citizen of the United States, and residing in the city of Chicago, county of Cook, and State 5 of Illinois, have invented certain new and useful Improvements in Stoves, of which I declare the following to be a full, clear, and exact description, reference being had to the accompanying drawings, forming a part of 10 this specification.

This invention has relation more particularly to cooking stoves or ranges such as are ordinarily used for domestic purposes, though features of the invention are susceptible of wider application. The invention consists in the features of novelty hereinafter described, illustrated in the accompanying drawings and particularly pointed out in the claims at the end of this specification.

20 Figure 1 is a view in central vertical section through a stove or range embodying my invention;

Fig. 2 is a view in horizontal section, this view being taken immediately beneath the 25 top of the stove;

Fig. 3 is a detail view in side elevation and Fig. 4 is a plan view of the hot blast pipe and the top support carried thereby;

Fig. 5 is a detail plan view of the top supporting plate for the fire pot;

Fig. 6 is a view in section on line 6—6 of Fig. 5;

Fig. 7 is a detail plan view of the lower supporting plate for the fire pot;

35 Fig. 8 is a view in cross-section on line 8—8 of Fig. 7;

Fig. 9 is a detail plan view of the fire pot;

Fig. 10 is a view in cross-section on line 40 10—10 of Fig. 9.

My invention is shown applied to a stove or range having an oven A within the outer wall B, the space between the oven A and the wall B serving as a flue for the products 45 of combustion that pass either by the exit ports b or b' to a smoke flue B'. As shown, the oven A is arranged with its lower portion next to the ash pit C and with its upper portion arranged adjacent the fire pot D, an 50 air chamber E surrounding the fire pot D and extending between the upper part of the oven A and the fire pot D. In the upper part of the oven opposite the fire pot D is provided a port or ports a through which 55 gases from the oven A may pass into the

chamber E and thence through the hot blast pipe F into the combustion chamber G above the fire pot D. The port or ports a are controlled by a sliding valve or plate a' of ordinary construction, this valve or plate a' being supported by the guides a² and a³ at top and bottom, and the movement of the valve being effected by a rod a⁴ that extends outside the stove or range. By means of the rod a⁴ the valve a' can be shifted so as to 60 partially or completely close the port or ports a adjacent the top of the oven A and thus cut off communication between the top of the oven and the air chamber E. The ash pit C is provided with the usual door C' 70 furnished with an ordinary draft valve.

The air chamber E is provided at its front with an admission port or ports e adapted to be controlled by a sliding plate valve e' that may be furnished with a projection or hand piece e² whereby the valve e' may be shifted. The valve e' is supported by the guides e³ and e⁴ located, respectively, at the bottom and top of the valve e'. The valves a' and e' are preferably of ordinary 80 "grid" construction and need not, therefore, be more fully described.

The top of the stove is shown as provided with the usual key plate or lid plate B², this plate B² being furnished with holes 85 as usual to receive the stove lids. In order to prevent the warping of the key plate B² and parts of the stove top above the combustion chamber and subjected to the intense heat at such points, I have provided 90 the hot blast pipe F, with a key plate or cover support f and with a bracket f' adapted to be bolted as at f² to the top of the oven A, these parts being formed preferably as an integral casting. As shown, the support f is formed with a notch f³ in its upper end to receive flanges projecting downwardly from the key plate and the adjacent part of the stove top.

Beneath the combustion chamber G is 100 placed the plate H that is formed with the flanges h and h' adapted to be bolted to the front plate of the stove and to the top of the oven A, respectively, as shown in Fig. 1. The plate H is also formed with an opening h² adapted to receive the fire pot D and with an opening h³ adapted to coincide with the lower end of the hot blast pipe F. The fire pot D comprises a unitary metal body that tapers from top to bottom and is 110

formed at its top with an outwardly projecting flange *d* adapted to rest upon the supporting plate *H*, and this flange *d* is cut away as at *d'* so as to permit the passage 5 of air from the air chamber *E* to the hot blast pipe *F*, as clearly shown in Fig. 1 of the drawings.

Beneath the fire pot *D* extends the bottom plate *K* of the air chamber *E*, this 10 plate *K* being formed preferably with the depending flanges whereby it is bolted to the front wall of the stove and to the wall of the oven *A*, as shown in Fig. 1 of the drawings. The bottom plate *K* and the top 15 plate *H*, respectively, cut off communication of the air chamber *E* with the ash pit *C* and combustion chamber *G*, and the bottom plate *K* serves also as a support for the lower end of the fire pot *D*. The depending 20 end flanges of the bottom plate *K* are shown as formed with holes *k'* to receive the rods that support the grate bars *L*.

While I have described what I regard as the preferred embodiment of my invention, 25 it will be understood that the details of construction above set out may be varied without departing from the spirit of the invention, and that features of the invention may be employed without its adoption as an 30 entirety. Thus, for example, while I have shown a single hot blast pipe *F*, it is obvious that two or more of such pipes may be employed.

By providing an air chamber *E* around 35 the fire pot *D* and between the combustion chamber *G* and the ash pit *C*, the air within the chamber *E* serves to cool the fire pot *D* and prevent it from rapidly burning out. So, also, the air within the chamber *E* 40 serves to prevent the excess heating of the upper part of the oven and insure a more uniform distribution of heat within the oven. So, also, the opening between the upper portion of the oven and the air 45 chamber also serves to permit the escape of gases from the oven into the combustion chamber through the hot blast pipe *F*. When air is admitted to the chamber *E* through the ports *a* or ports *e* it will be 50 come highly preheated before it passes upward through the hot blast pipe *F* into the combustion chamber *G*, and hence will be in condition to insure the most effective combustion of the gases within the chamber 55 *G*. Preferably, the hot blast pipe *G* is formed as a curved pipe, its upper end extending into the combustion chamber *G* above the fire pot *D*. The air passing up 60 through the pipe *F* also tends to modify the temperature of the pipe *F* and of the support *f*, and hence prolongs the life of these parts. The fire pot *D* can be readily removed from the plate *H* whenever replacement or repairs are required.

65 The air chamber *E* and pipe *F* are de-

signed to supply highly heated air to the combustion chamber and chiefly for economizing fuel when soft coal is employed. When first fed to the fire-pot large quantities of gases are driven off, and for effective combustion of the gases highly heated air must be intimately mixed therewith. The pipe *F* is open-ended and unobstructed, that is to say, it has substantially the same cross-section throughout, and 70 it extends inwardly over the fire-pot and has a down-turned outlet end portion so that it operates in a nozzle-like fashion to deliver the air passing from the chamber through the pipe with considerable force 75 downwardly into the upper central portion of the fire-pot. In this way the heated air is intimately mixed with the combustible gases passing from the coal in the fire-pot and practically complete combustion is effected. By means of the valves that control the air admission openings of the air chamber *E* the blast of air through the pipe can be regulated as desired or completely cut off, as for example, when the 80 coal is thoroughly coked.

Having thus described my invention, what I claim as new and desire to secure by Letters Patent is:—

1. In a stove, the combination with a casing and an oven therein, of a vertical wall on one side of said oven, upper and lower horizontal supporting plates fitting between and secured to said wall and the front wall of said casing and forming therewith a combustion chamber and an ash pit, said plates having openings therein, and a fire-pot body tapering from top to bottom, having flanged upper and lower edges for engaging the edges of the openings of said supporting plates and adapted to be inserted and removed as a unit through the opening in said upper plate, substantially as described. 95

2. In a stove, the combination with a casing, having an ash pit, a combustion chamber and an intermediate air chamber, of a horizontal supporting plate at the upper portion of said air chamber having an opening therein, a fire-pot removably fitting within said opening and extending into said air chamber and having a flange at its upper end overlapping said supporting plate, said plate and said flange being cut away to form a discharge port for heated air from said air chamber, and a hot blast pipe removably mounted above said flange, said pipe being in communication with said port and extending forwardly laterally over the fire-pot. 100

3. In a stove, the combination with a casing, having a combustion chamber, an ash pit and an intermediate air chamber, a horizontal supporting plate above said air chamber having an opening therein, a fire-pot removably inserted through said opening and extending into said air chamber and having 105

- a flange overlapping said supporting plate, said plate and flange being cut away at the rear side of the fire-pot to form a discharge port for heated air from said air chamber, 5 and a hot blast pipe removably mounted in position above said flange and connecting said port to said combustion chamber, said pipe having a supporting part for bracing the top of the stove casing.
- 10 4. In a stove, the combination of a casing having a fire-box surrounded by an air chamber, an oven at one side of the air chamber, a duct member leading overhead from the top of the air chamber and having 15 a discharge outlet directed downwardly toward the opening in the upper end of the fire-box, and selectively operable valve-controlled ports leading respectively from the oven and exterior of the casing into said air 20 chamber.
5. In a stove, the combination of a casing having a fire-box surrounded by an air chamber, an oven at the side of and separated from the air chamber by a vertical 25 partition, a duct member leading overhead from the top of the air chamber and having a discharge outlet directed downwardly toward the opening in the upper end of the fire-box, an opening in the aforesaid partition affording communication from the oven 30 to the air chamber, an opening in the wall of the casing affording communication from the exterior thereof to the air chamber, a valve for controlling each opening, and 35 means at the exterior of the casing for selectively operating said valves.
6. In a stove, the combination of a casing having an oven and a heating compartment separated by a vertical partition, an upright 40 flue at the side of the casing, a draft passage-way extending from the upper end of the heating compartment around the oven and having openings above and below the oven leading into the flue, a pair of vertically 45 spaced apertured plates in the heating chamber forming an ashpit therebelow and a combustion chamber thereabove, a firepot inserted downwardly through the aperture in the upper plate and seating against both plates 50 to form a closed air space around the firepot between the plates, an outlet opening in the upper partition between the firepot and oven, a duct member leading overhead from said opening and having a downwardly directed 55 discharge outlet substantially above the center of the fire-box, openings leading respec-
- tively from the oven and from the exterior of the casing into said air space, and valves selectively operable from the exterior of the casing for controlling said openings. 60
7. In a stove, the combination with the ash pit and combustion chamber, of an air chamber arranged between the ash pit and combustion chamber, a fire pot arranged within said air chamber, a valve for controlling the admission of air to said air chamber, a port at the top of said air chamber, and a hot blast pipe communicating with said port, extending over said fire pot and having a downturned discharge outlet 65 70 for directing heated air downwardly into the upper central portion of said fire-pot.
8. In a stove, the combination of a casing having a combustion chamber and an ash pit therein, a fire-pot arranged between said ash pit and combustion chamber, an air chamber surrounding said fire-pot and closed from communication with said ash pit, a valve for controlling the admission of air to said air chamber, and a hot blast pipe having 75 80 unobstructed inlet and outlet end portions communicating respectively with said air and combustion chambers, the discharge outlet end of said pipe being down turned and arranged above the central portion of 85 said fire-pot.
9. In a stove, the combination of a firepot having a combustion chamber thereabove, an oven separated from the firepot by an air chamber which is adapted to be heated 90 by said fire-pot, and a hot blast pipe arranged in said combustion chamber communicating with said air chamber and having a down turned discharge outlet portion extending over said fire-pot and adapted to 95 direct heated air into the upper central portion thereof.
10. In a stove, the combination with a casing having a combustion chamber, an ash pit, an intermediate fire-pot, an oven and 100 an air chamber closed from communication with said ash pit and arranged at the side of said fire-pot between the oven and firepot so as to be heated by the latter, a valve for controlling the admission of air to said air 105 chamber, and a hot blast pipe leading from the upper portion of said air chamber and extending over said fire-pot and having a down turned discharge outlet adapted to direct heated air downwardly into the upper 110 central portion of said fire-pot.

HUGH A. COLE.
